UNITED STATES PATENT OFFICE.

CLYDE C. FARMER AND THOMAS H. THOMAS, OF EDGEWOOD, PENNSYLVANIA, ASSIGNEES TO THE WESTINGHOUSE AIR BRAKE COMPANY, OF WILMERDING, PENNSYLVANIA, A CORPORATION OF PENNSYLVANIA.

AUTOMATIC LUBRICATOR.

Application filed March 25, 1921. Serial No. 455,603.

To all whom it may concern:

Be it known that we, CLYDE C. FARMER and THOMAS H. THOMAS, citizens of the United States, residents of Edgewood, in the county of Allegheny and State of Pennsylvania, have jointly invented certain new and useful Improvements in Automatic Lubricators, of which the following is a specification.

10 This invention relates to lubricators, and more particularly to an automatic lubricator for fluid compressors.

The principal object of our invention is to provide an improved automatic lubricator 15 of the type shown in Patent No. 1,337,687 of C. L. Bubb, dated April 20, 1920.

In the accompanying drawing, the single figure is a central vertical section of a lubricator embodying our improvements.

20 As shown in the drawing, the lubricator may comprise a casing or oil cup 1 adapted to be connected by a pipe 2 with the air cylinder of a fluid compressor.

Within the casing 1 is a chamber 3 containing the lubricant and in the neck portion of the cup is a threaded socket for receiving the threaded end of a cylindrical plug 4. Mounted on the plug 4 is a sleeve 5 having its lower end resting on a preferably machined face 6 of the casing 1 and having notches 7 to permit flow of lubricant from the oil chamber 3 to the annular capillary feed passage 8.

A port 9 connects the feed passage 8 with a central passage 10 in the plug 4, through which the lubricant is supplied to the compressor.

In order to maintain the sleeve 5 concentric with respect to the plug 4 and thus prevent the possible sealing of the port 9 by the engagement of the inner wall of the sleeve with the face of the plug 4, the feed passage 8 is provided by recessing the plug to a certain height, the remaining extent of the 45 sleeve being adapted to neatly fit the plug, so as to provide a guide for preventing any eccentric movement of the sleeve.

The upper end of the plug 4 is of enlarged diameter, so as to provide a shoulder 11 for the purpose of preventing the possible careless removal of the sleeve 5, when the lubricator is in use.

A cap 12 is screwed into a filling opening at the top of the oil cup and has a central

recess 13 for receiving the upper end of the 55 plug 4.

In order to prevent possible blowing of air and oil when the cap 12 is removed for filling while the compressor is running, a valve 14 is provided, subject to the pressure 60 of a spring 15, and having a stem 16 which extends through the passage 10 and is engageable by the cap 12 when the cap is screwed home.

Near the top of the plug 4, the passage 10 is reduced in diameter so as to provide a 65 snug fit for the stem 16 and thus guide the same.

An opening 17 is provided through the wall of the cap 12 near the top, so that when 70 the cap is slightly unscrewed, any pressure of air in the chamber 3 will be vented and consequently when the cap is removed there will be no danger of oil and air blowing out of the exposed oil filling opening of the cup. 75

Openings 18 extend from the passage 10 to the chamber 3 for permitting the equalization of pressure fluid, on the compression stroke of the compressor, into the space above the oil in the chamber 3. 80

When the cup has been filled with oil and the cap 12 screwed home, the stem 16 is pushed down by the cap, so as to hold the valve 14 off its seat and thus permit the flow of lubricant from the oil cup to the compressor. Upon removing the cap, the stem 16 is free to move and the spring 15 seats the valve 14 so that air pressure from the compressor cannot blow out while the oil cup is being filled with oil. 85

In operation, oil from the chamber 3 flows through the notches 7 to the annular feed passage 8 and then rises in said passage through capillary attraction so that oil is supplied to the port 9 and thence flows to the passage 10, from which the lubricant passes down past the valve 14 to the fluid compressor for lubricating the same. 90

Having now described our invention, what we claim as new and desire to secure by Letters Patent, is:—

1. In a lubricator, the combination with a lubricant holding cup, of an annular plug mounted in said cup and having a passage through which lubricant is supplied, a sleeve 105 mounted on and snugly fitting said plug at one portion of the sleeve and spaced from the plug at another portion of the sleeve to

- provide a restricted annular feed port, a port connecting the oil cup with the feed port, and a port connecting the feed port with the passage in the plug. 10
- 5 2. A lubricator comprising an oil cup having an oil chamber, a plug mounted in said oil cup and having an oil supply passage, a cap secured to said cup and having a recess for receiving the end of said plug, a valve con- trolling communication through said passage, a valve stem connected to said valve and extending through said passage, and ports in said plug leading from said passage to said chamber. 15
- In testimony whereof we have hereunto set our hands.

CLYDE C. FARMER.
THOMAS H. THOMAS.
